UNITED STATES PATENT OFFICE.

EMMA THOMPSON, OF BROOKLYN, NEW YORK.

CORSET.

SPECIFICATION forming part of Letters Patent No. 376,924, dated January 24, 1888.

Application filed July 21, 1887. Serial No. 244,891. (No model.)

To all whom it may concern:

Be it known that I, EMMA THOMPSON, a citizen of the United States, residing at Brooklyn, in the county of Kings and State of New York, have invented certain new and useful Improvements in Corsets; and I do hereby declare the following to be a full, clear, and exact description of the invention, such as will enable others skilled in the art to which it appertains to make and use the same.

My invention is an improved construction of corset, and one that is more especially designed for use as a nursing-corset, or whenever for any reason the wearer desires a corset which will permit of easy access to the breast, as in cases of an injury to or affection of the breast.

It also has for its object the addition thereto of a vest which may be used as a substitute for the underwaist worn by ladies, and, in connection with the other constructions, serves important functions and assists in finishing the corset, and whereby it can be rendered more ornamental than in the present forms.

In the drawings I have illustrated one form in which I have contemplated embodying my invention, and said invention is disclosed in the following specification and claims.

Figure 1 shows the front of my corset as applied to the body of the wearer. Fig. 2 is a side elevation of a part of a corset. Fig. 3 is a front elevation of the corset with the vest detached from the front thereof and extended above the same. Fig. 4 shows the corset in position for nursing.

A is the main corset-body, which is constructed in the usual manner, except that the front of the same is cut away at a a , as shown. This portion is preferably cut away so that the upper edge of the corset shall come below the breasts of the wearer. The part of the corset cut away at these points is filled by a knitted portion, a' a' , of a plain or lace-like texture, which are preferably provided at their upper edges with drawing-strings adapted to be tied at any convenient part of said edges.

To the back of the corset is attached the yoke-piece B, and to this yoke-piece is attached the vest C, composed of the parts c c . These two parts are united along their meeting edges by buttons, as shown, by hooks and eyes, or in any other preferred manner. These parts and

the yoke-piece B are cut away to form the neck-opening b .

When in position on the wearer, the vest is drawn over and down in front of the corset and covers and conceals the same, as shown in Fig. 1, the sides of the vest-pieces being attached to the corset by loops d , attached thereto and passing over hooks d' on the corset, or by buttons, or by the metallic hooks and eyes of commerce.

The front of the vest-pieces may be embroidered or otherwise ornamented to give a pleasing effect.

When it is desired to expose the breast of the wearer, the vest can be unfastened at the side and thrown back, as shown in Fig. 4, the drawing-string in the knitted portions of the corset-front loosened, and the knitted portion, being of light and loose texture, can then be easily pressed below and away from the breast.

The vest can be made of knitted material similar to that employed in jersey goods, which possesses a certain degree of elasticity and will fold away without creasing and yield sufficiently to aid in exposing the breast of the wearer. It serves to cover the corset at such times as desired, is easily removed, and when the child is nursing it can be replaced so as to cover the breast and the head of the child. These I regard as the more important functions of the vest, though it has the other advantages set forth herein.

In the drawings the corset is shown as provided with a full yoke provided with arm-holes E E and shoulder-straps or supports e e ; but I propose applying my improvements to all forms of corsets, whether provided with yokes or not, and to all waists used as substitutes for corsets.

What I claim, and desire to secure by Letters Patent, is—

1. A nursing waist or corset the main body of which is provided with cut-away portions for the breasts of the wearer, said cut-away portions being fitted with knitted material, substantially as described.

2. A nursing waist or corset the main body of which is provided with cut-away portions for the breasts of the wearer, fitted with knitted material, and vest-pieces attached to the corset and covering said breast portions and

the entire front of the corset, substantially as described.

3. The combination, with a waist or corset, of vest-pieces connected to the waist or corset near the top and also near the bottom of the same and covering the entire front of the corset, substantially as described.

4. The combination, with a corset or waist having knitted breast portions, of vest-pieces to each permanently secured to the said corset or

waist at one point and detachably secured to the same at another point, substantially as described.

In testimony whereof I affix my signature in presence of two witnesses.

EMMA THOMPSON.
